UNITED STATES PATENT OFFICE.

SENDER HANDEL, OF ST. LOUIS, MISSOURI.

FLESHING-MACHINE.

1,325,988.

Specification of Letters Patent. Patented Dec. 23, 1919.

Application filed December 27, 1918. Serial No. 268,462.

To all whom it may concern:

Be it known that I, SENDER HANDEL, a citizen of the United States, residing at the city of St. Louis, State of Missouri, have 5 invented certain new and useful Improvements in Fleshing-Machines, of which the following is a specification, reference being had to the accompanying drawings, forming a part thereof.

10 This invention relates to certain new and useful improvements in that class of machines commonly known as fleshing machines, which are employed more especially to remove fleshy matter from, and reduce 15 the thickness of, the pelt in the treatment of furs and skins for dressing.

The objects of my present invention are to provide a machine of the class stated which is of simple, durable, rigid, and inexpensive construction, and whose parts may 20 be conveniently assembled and replaced or renewed when necessitated by wear, breakage, or the like; to provide a machine of the class stated which is capable of operation 25 and use with substantially a minimum of knife "trouble" and whose knife is of a form and type adapted for convenient and repeated sharpening without replacement, the life of the machine being consequently 30 lengthened and its cost of maintenance reduced; to provide a machine of the class stated whereby efficiently fleshy-matter may be removed from the pelt and the thickness 35 of the pelt be reduced or skived, as I may say, with approximately a maximum of safety to both the operator and the skin or pelt from cutting or other injury, the dressing 40 of the skin or pelt being consequently facilitated and cheapened; and to improve generally upon, and simplify the construction of, machines of the class stated.

With the above and other objects in view, my present invention resides in the novel features of form, construction, arrangement, 45 and combination of parts hereinafter described and afterward pointed out in the claims.

In the accompanying drawings,

Figure 1 is a side elevational view of a 50 fleshing-machine embodying my invention, a portion of the body-guard being broken away;

Fig. 2 is a front elevational view of the machine; and

55 Fig. 3 is a sectional view of the machine

taken approximately on the plane of the shaft of its rotary knife.

Referring to the said drawings, in which like reference characters refer to like parts throughout the several views, the base of 60 the machine may be in the form of a suitable plate 1 adapted for support upon a suitable stand or the like (not shown) at an elevation suitable to the work. In the drawings, I show heads 2, which may represent suitable fastening-means, such as screws, engaging the base or plate 1 for rigidly securing the machine in installed position.

Upstanding from the base 1, is a pair of 70 spaced vertical standards 3—3, whose lower or foot-ends are preferably formed integral with the base and reinforced by suitable brace-webs 4—5, and whose upper ends are rigidly connected by a cross-member or head 6 bolted or otherwise suitably fastened thereto.

Intermediate their ends, the standards 3—3 are formed with relatively alined, horizontally disposed, and internally threaded 80 bores 7—7, in which are seated for adjustment screws 8—8 whose inner ends are conical in shape, as shown, and upon which a spindle 9, formed at its ends with conical-bearings 10 to receive the conical ends of 85 the screws 8—8, is mounted for rotation. Means, such as the pins 11, are provided for the convenient adjustment of the screws 8, and means, such as the jam or lock-nuts 12, are provided for locking the screws 8 in 90 adjusted position.

The spindle 9 is preferably threaded, as at 13, to conveniently receive, as seen especially in Fig. 3, a rotary disk-knife 14, a clamping-washer 15 disposed upon one side 95 of the knife 14, a belt pulley-ring 16 disposed upon the other side of the clamping-washer 15, and end-clamps 17—17 for rigidly keying the knife 14 and pulley-ring 16 to, and against displacement upon, the 100 spindle 9, each of the end-clamps 17 preferably including a non-circular hub 18 to facilitate their turning or adjustment upon the spindle 9 to effect such clamping upon the spindle of the knife 14 and belt-pulley 105 16. Seated in the clamp-hubs 18 to engage the spindle 9, are bolts or the like 19 for locking the end-clamps 17 in adjusted knife-and-pulley clamping-position upon the spindle.

The knife or blade 14, constituting the cutting element of the machine, is in the form of a relatively heavy one-piece circular or disk-shape steel-plate and is provided adjacent its periphery on its one or left-side flat face with a continuous annular channel or groove 20, whose outer margin forms with the periphery of the disk a knife or cutting-edge 21, the disk at its periphery being preferably shaped to provide a plain bevel face. The original cutting-edge 21 so formed may hence be conveniently sharpened or whetted by the simple application of an abrasive to the revolving periphery of the disk; and when such original cutting-edge 21 has been substantially worn away, it will be evident that new and succeeding cutting-edges may be readily provided upon the blade or disk 14, until the blade or disk 14 is itself substantially worn away and without removal or displacement of the disk from the machine, by the simple and convenient application to the side and peripheral faces of the disk of suitable abrasive or cutting-tools or the like to reproduce new and succeeding channels or grooves 20 and coöperating peripheral disk-faces. The disk or blade 14 may itself be facilely replaced or renewed when required, and not only does my new cutting-element lend itself to repeated and convenient sharpening without replacement, but arising also from this novel, relatively heavy, unitary construction of the cutting element are the distinct advantages that, in this class of machines which are usually operated at high speeds, the danger incident to the throwing off of loosened parts is substantially wholly eliminated, the breakage of the cutting element, both in use and in handling, is reduced approximately to a minimum, as obviously a knife or blade of my construction will withstand usage and strains which could not be withstood by the thinner, detachable, demountable, adjustable, and other varieties and types of knives now generally in use, the cutting-element itself rotates with reduced vibration and hence affords greater efficiency and accuracy in its work, and a structural economy is obtained, both in the use and assemblage of a single, self-supporting knife, and in the elimination of extraneous supports and braces.

The screw-bores 7 of the standards 3 project through bosses 22 on the standards, and mounted on the bosses 22 are suitable knife-guard supporting-brackets each including an inwardly-presented arm 23 and an elongated portion 24 projecting laterally from the arm 23 at its inner end and disposed adjacent a flat face of the disk or blade 14, the bracket-portion 24 being lengthwise bowed or convexed, as seen best in Fig. 2, to receive smoothly thereupon, and coöperate with, the correspondingly

bowed or convexed inner portion of a substantially segmental knife-guard proper 25. The guards 25 are opposed to each other, being complementingly disposed on opposite sides of the cutting-disk or knife 14, and combined present and afford a housing or guard of approximately lenticular section in which the knife or disk 14 revolves. Each guard-member 25 has an edge radius preferably somewhat greater than the radius of the knife-disk 14 and in use is so positioned relative to the rotary blade 14 as to expose only a portion of the periphery and cutting-edge of the blade at the working-point and to cover or overlie the periphery and cutting-edge of the blade from and on each side of the working point to points above and below the knife adjacent the standards 3, as illustrated in Fig. 1. And at the working-point, as seen in Figs. 1 and 3, the left-hand guard 25 projects at its outer margin preferably somewhat into the annular groove or channel 20, while the right-hand guard 25 smoothly meets at its outer margin the oblique or beveled periphery of the knife and provides, so to speak, a spaced extension thereof, whereby the "flesher" or operator is enabled to efficiently manipulate the skin or pelt across the rotating knife with a maximum of safety to both himself and the skin or pelt being worked. Each guard-member 25 is provided with transversely disposed slots 26-26 adapted to adjustably accommodate securing or fastening bolts 27-27 mounted in the supporting-bracket portions 24, whereby the guard-members 25 may be conveniently adjusted relatively to the knife 14 either for the purpose of regulating the depth of cut or compensating for variation or reduction in knife diameter due to wear and sharpening, any required relative axial adjustment of the cutting element and guards being conveniently accomplished by an axial movement of the cutting element by proper manipulation of the spindle-supporting screws 8. As shown in Figs. 1 and 2, the guard supporting-brackets are adapted for securement upon the standard-bosses 22 by means of set or fastening-screws or the like 28.

To safely protect the body of the "flesher" or operator from the otherwise exposed portion of the rotary-knife 14 opposite the housing-guards 25, I provide a body-guard 29, which is substantially a sheet metal hood provided at its lower margin with a hinged-extension 30 adapted for fastening, as by the screws 2, to the machine-base or plate 1, and at its upper margin with projecting ears 31 adapted for connection to the standards 3 as by means of screws or the like 32, which latter function also to secure the head 6 to the standards. The hood 29 not only affords safety

to the operator from the more or less rapidly rotating knife or cutting element of the machine, but also, by its described construction, it may be conveniently swung to open position by a simple removal of the securing-screws 32, without disturbing the cutting-element, its bearings or guard, or the relation of the machine to its supporting stand and hence the source of driving power.

To facilitate the introduction of necessary lubricant for rotation between the screw-bearings 8 and the spindle 9, the spindle 9 is preferably provided with suitable ducts 33; and it is to be understood that minor changes in the form, construction, arrangement, and combination of the several parts of my machine may be made and substituted for those herein shown and described without departing from the nature and principle of my invention.

Having thus described my invention,

what I claim and desire to secure by Letters Patent is:

1. A fleshing machine including a rotary knife of flat disk shape formed of a single piece of plate steel, the disk having in one side face a rounded groove extending annularly of the disk next its periphery, the outer wall of the groove forming with the peripheral portion of the disk the cutting-edge of the knife.

2. A fleshing machine including a rotary knife of disk shape formed of a single piece of relatively thick plate steel, the disk having a periphery beveled inwardly relatively to one side face and provided in its opposite side face and next its periphery with an annular rounded groove, the outer wall of the groove forming with the periphery of the disk a cutting edge.

In testimony whereof, I have signed my name to this specification.

SENDER HANDEL.
